UNITED STATES PATENT OFFICE.

GEORGE A. PROCTOR, OF LOS ANGELES, CALIFORNIA.

PACKAGE-OPENING MEANS.

Application filed April 18, 1925. Serial No. 24,074.

This invention relates to packages for cigarettes, or other merchandise, which are sealed or closed when sold or when packed, and the main object of the invention is to provide means whereby the package may be quickly and conveniently opened in such manner as to render the contents of the package easily accessible when desired but to firmly retain such contents until removed. A further object of the invention is to provide a package and opening means therefor of such type that after operation of the opening means the package may be readily manipulated so as to present a relatively large opening for the removal of the contents but may subsequently be so manipulated as to substantially close such opening and prevent loss or damage to the contents.

The invention comprises the combination, with a polyhedral package or container having its enclosing casing or a seal therefor wholly or partially formed of paper, foil, or other material capable of being torn, of a tearing device consisting of an elongated flexible cutting member such as a wire or thread suitably secured in said casing and adapted to be pulled so as to rip, cut, or tear the casing or seal of the package along or across adjacent sides thereof thus forming a slit or opening which extends across an edge of the package so that the package may be opened up by spreading or separating the parts of the package along the line of the cut or slit so formed, so as to enable the contents of the package to be easily removed or dispensed.

The accompanying drawings illustrate embodiments of my invention and referring thereto:

Fig. 1 is a front elevation of a cigarette package provided with opening means according to my invention.

Fig. 2 is a plan view of such package.

Fig. 3 is a vertical section of the package with part of the casing shown in elevation and with the tearing device in position for operation.

Fig. 4 is a transverse vertical section of the package shown in Fig. 1.

Fig. 5 is a perspective view showing the method of operating the tearing device and of opening the package and removing the contents.

Fig. 6 shows a simple type of tearing device for use in the above form of the invention.

The package indicated at 1 may consist of any desired or suitable number of wrappings or thicknesses of material as is common in such packages. For example it may comprise a layer of metal foil indicated at 2, a layer of paper as at 3, and an outer covering of waxed paper or other transparent material as at 4. The package or container may be formed and the cigarettes indicated at 5 may be packed therein in the usual manner of forming and filling such packages. My invention comprises in connection with such package an opening device comprising an elongated flexible cutting or tearing member 6, such as a wire or thread, secured at one end to the package or to securing means such as anchor member 7 suitably secured to said package or to the contents thereof, and at the other end to a tab or pull member 8, which is accessible for manipulation of the tearing device. The anchor 7 may comprise a stick or small rod of wood or other similar rigid material and may as in this case be secured in position by engagement with the upper corner of the package casing 1 as shown in Fig. 4. Since anchor member 7 is outside of the wrappings 2, 3, and 4, the tearing member 6 must extend through these wrappings at 85 this point. Anchor member 7 may be further held in place and prevented from slipping by means of a strip of paper or other material pasted over said member and extending over the top of the package. Such retaining strip may advantageously comprise the ordinary revenue stamp indicated at 31, when such a stamp is used. It may be mentioned here as an added advantage of my opening device, that operation of such device, as described below, to open the package, will at the same time tear the revenue stamp and thus prevent any possibility of re-use of such stamp. The tearing member 6 is preferably inserted in the package as shown so as to pass between the cigarettes and extend diagonally from a lower edge of the package to a non-adjacent or diagonally opposite upper edge thereof. By such an arrangement the tearing device lies in a substantially straight line and the pull exerted thereon in tearing the package is supported entirely by the anchor means, whereas if the tearing member lay along the top 21 and the side 20 so as to pass around an edge of the package or of the contents thereof, pulling on such member would cause inward

pressure at this edge and hence damage the contents of the package. Furthermore in the ordinary type of cigarette package with which the invention is particularly adapted for use, the package material is folded or doubled over at the top of the package so as to present a greater thickness of material at the top of the package than at the side of the package, and the revenue stamp is also affixed to the top of the package which serves to still further increase the thickness of the material at this point. It is a particular advantage of my invention in this connection that with the pull member 8 located at the bottom of a side wall of the package as indicated, the tearing operation is begun at the side wall of the package where a minimum thickness of material is presented and by the time the top of the package is reached the tearing member is already in motion so that the tearing can be continued across the top and through the greater thickness of material there presented without difficulty. If on the other hand an attempt were to be made to start the tearing operation in the top wall of the package, the greater thickness of the material at this point would render it practically impossible to make a clean cut through the same. Furthermore, it would be impossible to anchor or otherwise secure the end of the tearing device to the package strongly enough to support the pull required in such case.

The tab or pull member 8 secured to the other end of the wire or tearing member 6 may be conveniently located, as shown, near the bottom of the front of the package and in order to permit ready access to such tab, the wire or thread 6 may extend through the two inner wrappings 2 and 3 of the package, as indicated at 10, and said tab 8 may be placed between the wrapping 3 and the outer wrapping 4 of transparent material such as waxed paper. The tab 8 may advantageously be formed by providing a loop 11 at the end of the wire or thread 6 and covering such loop with suitable material such as paper or cloth to form a flat tab or handle as shown in Fig. 6. I also prefer to provide re-enforcing means, such as a strip of cardboard indicated at 9, inside the casing at the bottom of the package. In order to indicate the direction in which the tearing member is to be pulled, suitable indicating means such as an arrow indicated at 12 may be provided adjacent the tab or pull member 8 and extending in the direction in which the tearing member 6 is to be pulled. Such indicating means may be printed on the front of the package or it may consist of a small strip of paper or other material glued or pasted onto the outer wrapping 4 or the wrapping 3 at this point, or such indicator may be omitted.

In opening the above described package the outer transparent wrapping 4 is first broken adjacent the tab or pull member 8 and torn away as indicated at 13 so as to permit the user to grasp such tab and raise the same to the position indicated in Fig. 3. It will be seen that the pull member 8 may thus be grasped without any need of first opening the inner or main wrappings 2 and 3. The user may then pull on this tab in the direction indicated by arrow 12 and will thus pull the tearing member 6 through the wrappings 2, 3, 4, of the package so as to tear such wrappings upwardly along the middle of the front side 22 thereof and thence across the top 21 to the point at which the anchor member 7 is secured as indicated in Fig. 5. The anchor member may then be removed by pulling on the wire 6 so as to dislodge the same from under the covering, and the package may be opened by spreading the two sides thereof away from the slit 23 thus formed as also shown in Fig. 5. It will be seen that by virtue of the fact that the slit so formed extends across two adjacent sides of the package and consequently past an edge thereof, the package may easily be manipulated so as to present a relatively large opening for the removal of the cigarettes therefrom. Furthermore before or after one or more of such cigarettes have been removed the two halves of the package may again be brought together along the line of the cut or slit, so that the contents will again be securely retained within the package and loss thereof or damage thereto will be prevented. The re-enforcing means 9 serves to strengthen the bottom of the package and to cause the package, after opening, to tend to return to and remain in normal position with the sides of the package closed at slit 23.

My invention may also be applied in connection with other types or shapes of packages for permitting the removal or dispensal of any commodity contained therein; for example it may be applied to packages for cereals or breakfast foods, salt, etc. The particular place at which the slit is to be made will depend in each case upon the shape of the package and the character of the commodity contained therein. In general however it is essential that the wrapper or casing be made of material which is capable of being torn, and that the tearing device be so positioned within such wrapper or casing that when pulled it will tear the same along or across at least two adjacent sides and past or across at least one edge or corner so as to permit the parts at the two sides of the slits to be bent back to form a relatively large opening.

The above-described package opening means is to be distinguished from the type of package in which a strip or portion of

the wrapper or casing itself may be pulled off along or between certain lines by pulling on a portion thereof, as in such cases it is impossible to subsequently close the opening thus formed. It is also to be distinguished from, and is of material advantage over, the packages which are provided with lines of perforations in the wrapper along which it may be torn, such perforations having the disadvantage of preventing air-tight sealing of the contents of the package, which is oftentimes highly desirable. With my opening means the wrapping need only be pierced at the point at which the tearing member 6 extends through to the pull member 8, and in some cases at a similar point adjacent the anchor member, and these holes may be sealed if desired by application of a drop of glue or other sealing medium.

20 I claim:

1. In combination with a polyhedral package consisting of material capable of being torn, an opening device comprising an elongated cutting member extending in a substantially straight line within said package from a point intermediate the ends of one edge of said package, to a point intermediate the ends of a nonadjacent edge of the package in such manner that pulling upon one end of said cutting member will cause the same to cut across the sides of the package between said non-adjacent edges.

2. A construction as set forth in claim 1 and comprising in addition anchoring means secured to said package and also secured to one end of said cutting member so as to support the pull exerted upon said cutting member in the operation thereof.

3. A construction as set forth in claim 1, said cutting member having a portion projecting through said package at one of said edges and being provided with a tab secured to said projecting portion and located out-

side of said package so as to permit grasping of said tab for operation of the cutting member.

4. In combination with a polyhedral package consisting of material capable of being torn, an opening device comprising an elongated cutting member extending in a substantially straight line within said package from a point intermediate the ends of one edge of said package to a point intermediate the ends of a non-adjacent edge of the package, anchoring means secured to said package adjacent said first-named edge and also secured to the corresponding end of said cutting member, the other end of said cutting member projecting through said package, and a tab located outside of said casing adjacent said non-adjacent edge and secured to the projecting end of said cutting member.

5. In combination with a rectangular package comprising a casing consisting of material capable of being torn, an opening device comprising a thin flexible member extending in a substantially straight line within the casing from an intermediate point of an edge of one end of said casing to an intermediate point of the diagonally opposite edge of the other end of the casing, means securing said flexible member to the casing at one of said edges, means connected to said flexible member and protruding outside the casing adjacent said other edge to permit grasping thereof for operation of said opening device to tear said casing across the faces thereof between said diagonally opposite edges, and re-enforcing means located within one end of the package casing to tend to hold the package in closed position after operation of the opening device.

In testimony whereof I have hereunto subscribed my name this 7th day of April 1925.

GEORGE A. PROCTOR.
